DESIGN.

A. OLSSON.

TEXTILE FABRIC.

APPLICATION FILED JULY 17, 1916.

49,672.

Patented Sept. 19, 1916.

Inventor

Anna Olsson

By her Attorney

Michele Dallyn.

UNITED STATES PATENT OFFICE.

ANNA OLSSON, OF HARRINGTON PARK, NEW JERSEY, ASSIGNOR TO CHENEY BROTHERS,
OF SOUTH MANCHESTER, CONNECTICUT, A CORPORATION OF CONNECTICUT.

DESIGN FOR TEXTILE FABRIC.

49,672.

Specification for Design.

Patented Sept. 19, 1916.

Application filed July 17, 1916. Serial No. 109,851. Term of patent 3½ years.

To all whom it may concern:

Be it known that I, ANNA OLSSON, a citizen of the United States, residing at Harrington Park, Bergen county, State of New Jersey, have invented a new, original, and ornamental Design for Textile Fabrics, of which the following is a specification, reference being had to the accompanying drawing, forming a part thereof.

The figure is a plan view of a portion of a textile fabric, illustrating my new design.

I claim—

The ornamental design for a textile fabric, as shown.

ANNA OLSSON.

Witnesses:

HENRY L. SMITH,
JAMES C. MAYBERRY.
